UNITED STATES PATENT OFFICE.

AARON BEARSE, OF SYRACUSE, NEW YORK.

GUY-ANCHOR.

1,376,854.

Specification of Letters Patent.

Patented May 3, 1921.

Application filed June 27, 1917. Serial No. 177,210.

To all whom it may concern:

Be it known that I, AARON BEARSE, a citizen of the United States, residing at Syracuse, in the county of Onondaga and State 5 of New York, have invented a certain new and useful Guy-Anchor, of which the following is a specification.

This invention has for its object the production of a guy anchor which is particularly simple in construction, economical in manufacture and highly efficient and durable in use; and the invention consists in the novel features and in the combinations and constructions hereinafter set forth and 15 claimed.

In describing this invention, reference is had to the accompanying drawings, in which like characters designate corresponding parts in all the views.

20 Figure 1 is an elevation of a guy anchor embodying my invention, the wing being shown as folded against the rod of said anchor.

25 Fig. 2 is a view similar to Fig. 1, the upper portion of the rod being broken away and the wing being shown in longitudinal section and as in its unfolded position.

Fig. 3 is a plan view of the wing.

30 Fig. 4 is an enlarged detail view of the lower end of the rod.

This guy anchor comprises a rod and a wing foldably mounted on the rod into a position along the rod and into a position at an angle to the rod in order to obstruct 35 the pulling of the anchor out of the ground after the rod with the wing thereon has been driven in the ground, and pulled out far enough to spread the wing, one of said parts being formed with a slot through 40 which the other of said parts extends and the latter part being formed with shoulders for limiting the tilting movement of the wing.

1 designates the rod, and 2 the folding 45 wing. As here shown, the wing 2 is formed with a base 3 having an enlarged opening as an elongated slot 4 for receiving the rod, and the rod is formed with opposing shoulders 5, 6 above and below the base, the shoulder being spaced apart a greater distance than the thickness of the base 3 of the wing 50 in order to permit the folding movement of the wing, the base being arranged at an angle to the blade or major part of the wing 55 3 and the shoulders 5, 6 being spaced apart such distance that the ends of the base en-

gage said shoulders and limit a tilting movement of the wing relatively to the rod 1 when the blade of the wing assumes a position approximating a right angle to the 60 rod 1. The rod may be formed in one piece and the base 3 of the wing split as indicated at 7 in order to open the slot on one side or end and permit the base to be placed on the rod between the shoulders 5, 6, or as seen in 65 Fig. 3, the head 8 of the rod may be provided with a shank which is driven into a socket 9 in the lower end of the major part of the rod, the lower end of the major part of the rod and the rear end or barb of the 70 head serving as shoulders 5, 6 for the wing 2.

In this latter construction, the inner end portion of the socket is enlarged in order that during the driving of the rod into the 75 ground the end of the shank in the socket will be spread or riveted in the socket and hold the head from detachment, or as indicated in dotted lines in Fig. 1 the point may be threaded into the major part of the rod. 80

In operation, the rod is driven into the ground and then pulled outwardly causing the wing 2 to move from the position shown in Fig. 1 to that shown in Fig. 2, in which the base 3 assumes an inclined position relatively to the rod, and the end walls of the 85 slot 4 engage the rod or the ends of the base engage the shoulders 5, 6.

What I claim is:

1. A guy anchor comprising a rod having 90 a point at its advance end and a wing foldably mounted on the rod to the rear of the point and foldable into a position along the rod and into the position at an angle to the rod, the wing being formed with a base 95 rigid therewith which coacts with the rod, one of said parts being formed with a lengthwise slot and the other of said parts extending through the slot and having shoulders spaced apart at the rear of the 100 point, the slot and the shoulders being arranged to permit an endwise and rocking movement of the wing relatively to the rod and limit the movement of the wing from rocking movement when the wing assumes 105 a position approximating a right angle to the rod.

2. A guy anchor comprising a rod having a point at its advance end, and a wing foldably mounted on the rod in the rear of the 110 point and foldable into a position along the rod and into a position at an angle to the

rod, the wing being formed with a base rigid with the blade of the wing and arranged at an angle to the blade of the wing and formed with a lengthwise slot for receiving the rod and the rod being formed with shoulders spaced apart for permitting tilting of the base and limiting the tilting movement thereof when the blade of the wing assumes a position approximating a position at a right angle to the rod, substantially as and for the purpose described.

3. A guy anchor comprising a rod having shoulders thereon spaced apart and a point in advance of the lower shoulder, a wing

having a base rigid therewith and mounted on the rod between the shoulders and having a slot for receiving the portion of the rod between the shoulders, the base being of less thickness than the distance between the shoulders and the base being arranged at an angle to the blade of the wing, substantially as and for the purpose set forth.

In testimony whereof, I have hereunto signed my name at Syracuse, in the county of Onondaga, and State of New York, this 2nd day of March, 1917.

AARON BEARSE.
